BATHROOM VANITY UNIT

Myron J. Ament, Bethel Park, Pa., assignor to Wallace-Murray Corporation, Pittsburgh, Pa.

Filed July 27, 1971, Ser. No. 164,491

Term of patent 14 years

Int. Cl. D23—02

U.S. Cl. D23—49

FIG. 1

FIG. 2

FIG. 3

FIG. 4

FIG. 5

FIG. 1 is a perspective view of the bathroom vanity unit embodying my new design;

FIG. 2 is a top plan view thereof;

FIG. 3 is a bottom plan view thereof;

FIG. 4 is a front elevational view thereof; and

FIG. 5 is a side elevational view thereof.

The rear of the unit is generally hollow and unornamented.

I claim:

The ornamental design of a bathroom vanity unit, as shown and described.
